UNITED STATES PATENT OFFICE.

STACY B. HASELTINE, OF CHICAGO, ILLINOIS, ASSIGNOR TO WILLIAM H. MINER, OF CHAZY, NEW YORK.

HAND BRAKE.

Application filed May 8, 1922. Serial No. 559,168.

To all whom it may concern:

Be it known that I, STACY B. HASELTINE, a citizen of the United States, residing at Chicago, in the county of Cook and State of Illinois, have invented a certain new and useful Improvement in Hand Brakes, of which the following is a full, clear, concise, and exact description, reference being had to the accompanying drawings, forming a part of this specification.

This invention relates to improvements in hand brakes.

An object of the invention is to provide a hand brake for railway cars of efficient and economical design and so arranged as to render it easy for the brakeman to operate the brake with one hand while holding on with the other to steady himself.

Other specific objects of the invention are to provide an improved releasing device and improved means for attaching the end of the brake chain to the drum.

In the drawing forming a part of this specification, Figure 1 is a vertical, sectional view in a plane perpendicular to the end wall of a car and corresponding to the section line 1-1 of Figure 2, illustrating my improvements as applied to the end wall of a gondola or other freight car. Figure 2 is a vertical, sectional view, corresponding substantially to the section line 2-2 of Figure 1. Figure 3 is a detail, sectional view, taken on the broken line 3-3 of Figure 1. And Figure 4 is a detail, sectional view, corresponding to the line 4-4 of Figure 2 and illustrating more particularly the means for attaching the end link of the brake chain.

In said drawing, 10 denotes the end wall of a car to which my improved brake mechanism is adapted to be attached. In carrying out my invention, I employ what may be termed a housing, casing or bracket, designated generally by the reference character A; a rotatable chain-winding drum B; a ratchet wheel C; a carrier or hanger D; an operating lever E; a locking dog F; and a release lever G.

The housing or bracket A is preferably provided with an inner vertically extending wall 11 by which the bracket is secured to the end wall of the car. In addition, the bracket A is formed with a top wall 12 which is extended horizontally for a distance and then curved downwardly and for-

wardly as indicated at 12^a so as to provide a hood or shield for the operating parts within the bracket. In addition, the bracket A is formed with an integral end wall 13, an intermediate partition 14 and an end wall 15. In this connection, while I have shown the end walls 13 and 15 as integrally formed with the remainder of the bracket, it will be understood that the end wall 15 may constitute a part of a casting separate from the remainder of the bracket and such modified construction is intended to be included within the term "bracket" or "housing" as herein used in the description and claims. The bracket is open at the bottom, as clearly shown in Figures 1 and 2 to provide the necessary clearance for the operating elements and for the passage of the brake chain.

The rotatable drum or chain-winding member B has a cylindrical portion 16 journaled at its lefthand end, as viewed in Figure 2, in a suitable bearing 15^a. The righthand end of the member B is preferably of non-circular cross section, in the instance shown being square, as indicated at 17 and mounted on the section 17 is the ratchet wheel C so that the latter rotates in unison with the member B. The ratchet wheel C, at the end nearest the cylindrical portion 16 of the member B, is of maximum diameter and cylindrical so as to provide a journal 18 rotatably mounted in a bearing 14^a provided in the partition 14. To the right of the section 18, the ratchet wheel C is of reduced diameter as indicated at 19 and the latter, at its righthand end as viewed in Figure 2, provides a bearing for one wing 20 of the oscillatable carrier D, the other wing 21 thereof being freely rotatable on the section 18 of the ratchet wheel. As best shown in Figure 1, the wings 20 and 21 are united at their outer ends by an arcuate web 22 which, when the parts are in their normal release position as shown in Figure 1, provides an additional weather shield for the operating parts. The ratchet teeth 23 of the ratchet C are located intermediate the wings 20 and 21 and adapted to cooperate therewith is a tooth or pawl 24 of the operating handle E which is pivoted to the carrier D on the rivet or other pivot-forming member 25. The operating handle E normally depends in a vertical inoperative position, as best shown in Figure 1.

To prevent the chain unwinding acci-

dentially, I have provided the dog F which is pivoted on a stud 26 preferably made integral with the end wall 13 of the bracket A, as clearly shown in Figure 3. The dog F 5 has a single tooth 27 adapted to cooperate with the same ratchet teeth 23 as does the operating pawl 24. The dog F is normally held in engagement with the ratchet wheel by means of a suitable expansion spring 28 10 which is seated at its ends over small lugs on the back wall and dog F, respectively. To release the dog F, the release lever G is provided, the same being pivoted on a rivet or other suitable pivot-forming member 29 15 sustained by the end wall 13 and partition 14 of the bracket casting A. Said lever G has a handle proper 30 which extends downwardly and outwardly away from the end wall of the car, in normal position of the 20 parts, as shown best in Figure 1. On the opposite side of the pivot 29, the lever G is provided with spaced short arms 31—31 which are slotted at their upper ends to provide vertically extending recesses 32 and 25 within which are engaged the laterally extended ends of a pin 33 carried by the dog F. In this manner, it will be observed that a loose toggle joint is effected between the lever G and the dog F so that, when the 30 brakeman pulls up the outer end of the lever G, the dog F will be retracted from the ratchet wheel and furthermore a high leverage ratio is obtained which is an advantage particularly where the teeth of the ratchet 35 wheel are undercut as shown in the drawing, inasmuch as, in pulling the dog F from the ratchet wheel, the latter must be advanced slightly against the tension of the brake chain.

40 In order to attach the end link 34 of the brake chain in a convenient and effective manner to the winding member, I preferably employ the following arrangement. Detachably mounted on the squared section 45 17 of the member B and up against the shoulder 35 provided at the end of the cylindrical section 16, is a plate 37 having a depending flange 38 with an opening 39 therethrough. The flange 38 is of lesser thickness than the thickness of the main part of the plate 37 so that a space is left between the flange 38 and another small plate 40 which is countersunk into a suitable recess 41 provided on the adjacent end 50 of the ratchet wheel C. Said small plate 40 is provided with a finger 42 extending horizontally and adapted to enter the opening 39. With this arrangement, a separable ring 55 effect is obtained between the plates 37 and 40 by which the end link 34 is attached when the finger 42 is inserted through the link, as best shown in Figure 2.

60 To assemble the parts, after the bracket A is riveted to the end wall of the car, the

hanger D is inserted within the chamber defined between the end wall 13 and partition 14. The ratchet wheel C is then slipped endwise through the bearing 14^a and assembled with the hanger D. The plate 40 is next put in position in the recess 41 and the end link 34 hooked thereover, after which the member B is inserted longitudinally through the bearing 15^a and the plate 37 telescoped thereover until all the parts are brought to the position best shown in Figure 2. To hold the parts in assembled position, a cover plate 43 is applied over the end of the member B and held in position by any suitable means such as the bolts and nuts 44.

65 By arranging the member B so as to rotate about a horizontal axis parallel with the end wall of the car, the brakeman is enabled to grasp either the operating handle E or the release lever G with his right hand and pull up while standing on the usual step and in this way exert great force in either applying the brakes or in releasing the drum. At the same time, the brakeman may steady himself by taking hold of the usual grab iron with his left hand, thereby minimizing danger of injury, due to sudden giving away of any part or sudden change of 70 speed of the car.

75 I claim:

1. In a hand brake mechanism, the combination with a bracket adapted to be secured to a car wall; of a horizontally extending chain-winding member rotatably supported in said bracket; ratchet means for rotating said member step by step in a winding direction; means preventing accidental rotation of said member in an unwinding direction; and means for attaching the end link of the chain to said member including, two elements relatively longitudinally movable lengthwise of said member and having co-operable interlocking parts, one of said parts having a finger extending through the end link to thereby lock the latter between said elements when the elements are assembled.

100 2. In a hand brake mechanism, the combination with a bracket adapted to be secured to a car wall; of a horizontally extending chain-winding member rotatably supported in said bracket; ratchet means for rotating said member step by step in a winding direction; means preventing accidental rotation of said member in an unwinding direction; and means for attaching the end link of the chain to said member including, a plate telescoped on said member and another element mounted on said member adjacent thereto, one of said elements being provided with a finger extending into the other element, said finger being adapted to pass through said end link of the chain.

105 3. In a hand brake mechanism, the com-

- bination with a bracket adapted to be secured to a car wall; of a horizontally extending chain-winding member rotatably supported in said bracket; ratchet means for 5 rotating said member step by step in a winding direction; means preventing accidental rotation of said member in an unwinding direction; and means for attaching the end link of the chain to said member including, 10 a plate telescoped on said member and having a radially extending flange, a second element telescoped on said member adjacent said first element, and a plate countersunk into said second element and having a finger 15 interlocking with the first mentioned element, said finger being adapted to extend through said end link.
4. In a hand brake mechanism, the combination with a bracket adapted to be secured 20 to a car; of a member rotatably mounted on said bracket adapted, when rotated, to produce tension on the brake chain; means for rotating said member step by step in a winding direction; and manually releasable 25 means for preventing accidental rotation of said member in an unwinding direction including, a ratchet wheel rotatable in unison with said member, a dog cooperable with the ratchet wheel and pivotally supported on 30 said bracket, a lever pivotally supported on said bracket, said lever being provided with an operating handle on one side of its pivot and an arm having loose toggle engagement with said dog.
- 35 5. In a hand brake mechanism, the combination with a bracket adapted to be secured to a car; of a member rotatably mounted on said bracket adapted, when rotated, to produce tension on the brake chain; means for 40 rotating said member step by step in a winding direction; manually releasable means for preventing accidental rotation of said member in an unwinding direction including, a ratchet wheel rotatable in unison with 45 said member, a dog cooperable with the ratchet wheel and pivotally supported on said bracket, a lever pivotally supported on said bracket, said lever being provided with an operating handle on one side of its pivot
- and an arm having loose toggle engagement 50 with said dog; and a spring yieldingly holding said dog in engagement with the ratchet wheel.
6. In a hand brake mechanism, the combination with a bracket adapted to be secured 55 to a car; of a member rotatably mounted on said bracket about a horizontal axis and adapted, when rotated, to produce tension on the brake chain; means for rotating said member step by step in a winding direction 60 and including, a ratchet wheel; a dog pivotally mounted on said bracket about a horizontal axis; a release lever pivotally mounted on a horizontal axis on said bracket and operatively connected with said dog, said 65 release lever having an outwardly and downwardly extended handle influenced by gravity to normally maintain the dog in operative relation with said ratchet wheel.
7. In a hand brake mechanism, the combination 70 with a bracket adapted to be secured to the end wall of a car; of a chain-winding drum mounted on said bracket to rotate about a horizontal axis parallel to the end wall; means for rotating said drum step by 75 step in a winding direction and including, a ratchet wheel and a gravity drop operating handle oscillatably mounted with respect to the drum; a locking dog pivotally mounted on said bracket to cooperate with said 80 ratchet wheel; a spring normally influencing said dog to operative position with respect to said ratchet wheel; and a release lever pivotally mounted on said bracket about a horizontal axis and operatively connected 85 with said dog, said release lever having a handle normally extending downwardly and outwardly from the bracket whereby said operating handle and release lever may be oscillated in planes perpendicular to the end 90 wall of the car.
- In witness that I claim the foregoing I have hereunto subscribed my name this 29th day of Apr. 1922.
